VALVE FOR INTERNAL COMBUSTION ENGINES

Roland Claude Cross, Odd Down, Bath, Somerset, England

Application December 20, 1933, Serial No. 703,299
In Great Britain December 23, 1932

5 Claims. (Cl. 123—190)

This invention relates to improvements in rotary valves, such as rotary valves for internal combustion engines, and is a modification of the invention set forth in the specification of my prior Patent No. 1,887,997 dated November 15th, 1932. The said prior case refers to valve assemblies for internal combustion and other engines wherein a valve element rotates within a bearing surface and by means of exhaust and inlet ports therein is used to control the opening and closing of a port or ports in the bearing element; an essential feature in the construction of my said prior invention is a bearing liner which is fixed in or to the valve housing and has a port or ports formed or surrounded at the surface of said liner with which the valve coacts by a resilient lip pressed up from said liner and having an unbroken or continuous edge. This lip tends to project into the space occupied by the valve and is normally pressed back by the valve to form a fluid-tight seal.

The object of the present invention is to keep the temperature of the resilient lip as low as possible, and this is accomplished by shielding it to some extent from the exhaust flame whilst allowing it to project into the path of the cooling inlet gases as much as possible.

According to the present invention the edge of the said resilient lip is mainly covered by the edge of the exhaust port in the valve when they register. For example, the exhaust port in the valve is made of smaller area than the port in the liner, whilst preferably also the inlet port in the valve is made larger. The effect aimed at is to cause the edge of the valve port to align with or overlap the lip edge, or a substantial length thereof during exhaust, whilst the edge of the other valve port is disposed back away from the lip edge—regarding their position of operation or register—to allow the latter (for all or most of its length) to project into the inlet valve port area during the suction stroke.

The invention will be better understood by reference to the accompanying drawing, wherein:

Figure 1 is a vertical section of the upper part of an internal combustion engine fitted with a rotary valve controlling the inlet and exhaust of the cylinder according to the invention;

Figure 2 is a fragmentary view to a larger scale according to Figure 1 showing the exhaust port of the valve in its position of register or operation;

Figure 3 is a view similar to Figure 2 but showing the inlet port in operation;

Figures 4 and 5 are port diagrams hereinafter described.

Referring to the drawing there is provided a thin bearing liner or bush 1, which is shrunk or otherwise fastened in the valve housing 2, and in which the valve 3 rotates to perform its work of opening and closing the port 4 in the valve housing leading to the cylinder head 5. This liner 1 has a port opening 6 in its wall permanently communicating with the port 4, and the said liner, at that part of it which forms the periphery of the said port opening is shaped with a lip 8 so as to press slightly inwards towards the working face of the valve 3, so that the edge of the said port opening is resiliently pressed against the wall of the valve. This gives the valve a good working clearance in the liner, and whatever position the valve assumes in the liner the said lip 8 will resiliently follow the surface of the valve, thereby making it sufficiently gas-tight for all practical purposes.

The clearance between the valve 3 and the liner 1 is necessarily greatly exaggerated in the drawing to show the deflected lip 8, but in practice the lip is pressed substantially back to the plane of the working surface of the liner when in the assembled position.

The valve 3 is formed with an inlet port 10 and an exhaust port 9 which, in turn, during the rotation of the valve, come into register with the lipped port 6 in the liner 1. As seen in Figures 1 and 2 the exhaust port 9 is of smaller area than the lipped port 6 of the liner so that the edge of port 9 overlaps the resilient lip 8. Conversely the inlet port 10 is of greater area than the lipped port 6 so that in this case the lip 8 is the overlapping edge when ports 6 and 10 are in register as in Figure 3.

In the embodiment according to Figures 1-3, the various ports are shown as either circular or elliptical. They may be of other configuration. If the various ports are of square or other polygonal formation then all the side edges or some of them may be set to produce the effect aimed at. Figures 4 and 5 are show diagrams of rectangular ports, the exhaust port 9 of the valve being depicted in cooperative registration with the liner port 6 and overlapping same in Figure 4, whilst the port 6 is shown overlapping the inlet port 10 in Figure 5. The overlapping is shown as taking effect at every side of the ports.

With circular or elliptic ports as in Figures 1-3, the edges of the ports in the liner and valve respectively may be parallel or concentric when in the coincident or registering position. The

amount of overlap of the resilient lip 8 into the valve port area or vice versa need not necessarily be symmetrical all round the perimeter of the port.

5 I claim:—

1. A valve assembly comprising a valve housing having a port, a valve having an exhaust port for cooperation with said housing port, a valve bearing element interposed between the valve and the housing and having a port permanently communicating with the housing port, and a resilient lip integral with the bearing element surrounding the port therein, and tending to project into the space occupied by the valve whereby it seals fluid-tight against the valve, the edge of the said lip being mainly covered by the edge of the said exhaust port in the valve when they register.

2. A valve assembly as set forth in claim 1 in which the edge of the resilient lip forms a port area greater than that of the exhaust port in the valve.

3. A valve assembly as set forth in claim 1 in which the valve has an exhaust port and an inlet port for cooperation with the housing port, and in which the edge of the resilient lip is mainly uncovered by the edge of the said inlet port in the valve when they register.

4. A valve assembly as set forth in claim 1 in which the valve has an exhaust port and an inlet port for cooperation with the housing port, and in which the edge of the resilient lip forms a port area less than that of the inlet port in the valve.

5. A valve assembly comprising a valve housing having a port, a cylindrical valve bearing element disposed within said housing and having a port permanently communicating with the housing port, a cylindrical valve within said bearing element provided with exhaust and inlet ports for cooperating with the housing and bearing element ports, and a resilient lip integral with said bearing element, surrounding the port therein, and tending to project at its free edge into the interior of the bearing element whereby it seals fluid-tight against the valve, the said exhaust port in the valve being of such an area that its margin overlaps the said lip of the bearing element and the said inlet port in the valve being of such an area that it is overlapped by the said lip of the bearing element when the lip and port respectively register.
